UNITED STATES PATENT OFFICE.

VINCENT A. BUCHHOLTZ, OF CUMBERLAND, MARYLAND.

LICENSE-PLATE HOLDER FOR AUTOMOBILES.

1,360,880.

Specification of Letters Patent. Patented Nov. 30, 1920.

Application filed May 28, 1920. Serial No. 385,045.

To all whom it may concern:

Be it known that I, VINCENT A. BUCHHOLTZ, a citizen of the United States, residing at Cumberland, in the county of Allegany, State of Maryland, have invented certain new and useful Improvements in License-Plate Holders for Automobiles, of which the following is a description, reference being had to the accompanying drawing and to the figures of reference marked thereon.

This invention relates to devices for securing number plates or license tags to automobiles, and more particularly to a simple device for enabling the rapid and facile attachment of the tag to its supporting bracket.

The primary object of this invention is to provide a device of the above character which can be inserted into either registering holes or slots in the bracket and tag members by a slight pressure on the thumbhold and which will thereafter lock the members by a slight turn of the device or by swinging the pivoted lock bar transversely to the position it occupied when passing through the registering apertures.

A further object of the invention is to provide a device of the above character composed of the simplest number of parts and which can be easily assembled during the process of manufacture.

These and other objects will in part be obvious and will in part be hereinafter more fully disclosed.

In the drawings which show by way of illustration one embodiment of the invention:—

Figure 1 is a perspective view of the device holding the license sign in place, and

Fig. 2 is a sectional view showing the construction of the holder.

Referring more particularly to the accompanying drawing, a license tag 1 having the usual holes 2, which also may be in the form of slots, is adapted to be attached to any desired form of bracket 3, which, in the present case, is shown as elongated and provided with an extended slot 4. The holder

50 which comprises the feature of this invention includes a metallic shank 5 provided on its outer end with an integral flat thumbhold or wing nut 6 having an inner shoulder 7, the inner shoulder 7 constituting an abutment hereinafter set forth. The inner end of the shank 5 is slotted as shown at 8,

providing two spaced ears 9 between which is pivotally mounted, as at 10, a lock bar 11.

In the preferred form, the anchor pin 10 for this lock bar is given a slight amount of 60 play by elongating the slot 12 in the lock bar 11. This is for the purpose of permitting the lock bar to swing more easily to the transverse locking position.

Loosely surrounding the shank 5 is an 65 annular soft rubber washer 13, which, at each end, is provided with a metallic facing comprising a preferably sheet metal washer 14 having an inturned annular flange 15 crimped or otherwise forced into the inner 70 bore of the rubber washer 13. In this manner, the rubber washer is provided with a facing at each end, which facings are permanently united thereto in a most effective and simple manner.

In using this device, the round hole 2 of the license tag is brought into register with a slot 4 of the bracket, and then by compressing the rubber washer toward the thumbhold, the lock bar may be swung into line 80 with the axis of the shank and the shank of the holder then inserted through the registering holes of the tag and bracket, after which the lock bar is swung to a transverse position to hold the bracket and tag in 85 proper position. If the license tag is provided with an elongated slot instead of a hole, the holder can be inserted through the registering longitudinal slots of the bracket and tag respectively, and then by holding 90 the wing nut firmly between the thumb and forefinger, the rubber washer can be compressed and the shank given a half turn, so that the lock bar will lie transversely across the slot of the bracket to hold the tag in 95 supported position. It is of course obvious that instead of using two of these holders as shown in Fig. 1, any suitable arrangement may be availed of whereby one will hold the tag and bracket in supported position.

It will be noted that a device of this character is entirely rust-proof, is very simple in construction, and is effective to hold the bracket in position and prevent it from rattling.

The metallic facings for each end of the rubber washer constitute rigid surfaces against which the bracket or tag abut at the one end, and the shoulder 7 of the thumbhold abuts at the other end. So also, the 110 integral thumb-hold provides a very effective means for turning the lock bar while

the rubber washer is under compression due to the inward pressure on the thumb-hold.

It will also be understood that various modifications may be made in the details of 5 construction without departing from the spirit of the invention as set forth in the appended claim.

Having thus described the invention, what I claim as new and desire to secure by Letters Patent, is:—

The combination of an apertured supporting bracket and an automobile number plate having an aperture adapted to register with the aperture of the bracket, a holding device therefor comprising a shank 15 adapted to pass through said apertures and

formed with an integral wing nut on its outer end, an annular rubber washer loosely surrounding said shank, a pair of sheet metal washers, each secured to and forming a facing for the end of said rubber washer and each having an inwardly turned flange surrounding said shank, and a fastening pin pivotally mounted on the inner end of said shank and adapted to be swung 20 transversely of the longitudinal axis of said shank to hold said number plate to said bracket.

In testimony whereof, I affix my signature.

VINCENT A. BUCHHOLTZ.
